UNITED STATES PATENT OFFICE.

PAUL O. KUEHN, OF SOUTH BEND, INDIANA.

BOOK-INDEX.

1,390,623.

Specification of Letters Patent. Patented Sept. 13, 1921.

Application filed February 21, 1919. Serial No. 278,474.

To all whom it may concern:

Be it known that I, PAUL O. KUEHN, a citizen of the United States, residing at South Bend, in the county of St. Joseph and State of Indiana, have invented certain new and useful Improvements in Book-Indexes, of which the following is a specification.

The invention relates to improvements in book indexes, and the primary object there-
10 of resides in the provision of an index applied to the front edge of the book in a manner to render the entire index indicia visible at a glance, and without the necessity of first shifting the book to one side and then to the
15 other in order to render visible index indicia applied to the side marginal edge of a leaf, and exposed to view by thumb notches cut in the adjoining leaves, as is the method most commonly employed. A further ob-
20 ject resides in the provision of an index which, unlike indicia applied by printing and easily worn away, will have a more permanent form, and not easily obliterated or rendered illegible, as by being worn away
25 by constant fingering in paging the book. A still further object consists in applying index indicia to the front edge of the book in intaglio form, so that such indicia at the same time serves as a thumb grip to facilitate
30 separation of the leaves at the desired point.

With the above and other objects in view, the invention in the preferred form of de-
35 tails will be described in the following speci-
fication, reference being had particularly to
the accompanying drawings, in which:—

Figure 1 is a perspective view of a book embodying the improvement.

Fig. 2 is a fragmentary view representing the edges of the leaves of a book, with
40 an index letter applied in accordance with the invention, and as viewed in perspective.

The indexing indicia to be used, as for example, letters of the alphabet, and as shown in Fig. 1, are formed on the front edges 1 of the leaves of the book, so that all of the letters will be visible at a glance, with the book held in the natural and most commodious position for opening the book at the desired point. The value and ad-
50 vantage of such application and arrangement of the indexing indicia, in permitting the instant locating of the subject matter,

will be clearly apparent, especially in the saving of time and labor when reference must be had to many books, as in the making of researches, looking up law points, finding names and addresses, etc.

Instead of applying the index letters 2 by printing or stenciling the same, the letters are formed in any suitable manner, as by cutting or etching the same with acid, so as to be sunken or recessed with respect to the edges of the leaves. The letters thus formed are sufficiently distinct and visible without distinctively coloring the same, and are not unsightly or unduly prominent. In practice the letters would be so arranged relatively that the left extremity of each letter would indicate the point for paging the book to find the beginning of the subject matter indexed thereby. Inasmuch as the sunken or recessed index letters also form a thumb grip for ready separation of the leaves, no special thumb notches are necessary for that purpose. It will also be apparent that the index letters will not readily become worn away or illegible by constant thumbing thereof in paging the book, as occurs where such are applied by printing or stenciling.

Having thus described the invention, what is claimed is:—

1. The combination with a book having a plurality of leaves, of an index therefor, said index forming finger engaging recesses, 85 said index consisting of indicia formed by removing portions of the edges of contiguous leaves in such a manner that when the contiguous leaves are in engagement with each other, a complete outline of the indicia 90 will be formed in sunken relation to the edges of the leaves.

2. The combination with a book having a plurality of leaves, of a combined index and finger engaging recesses therefor, said index 95 and finger engaging recesses being in sunken relation to the edges of the leaves and formed by removing portions of the edges of contiguous leaves in such a manner that when the leaves are brought together the 100 outline of the indicia is formed in sunken relation to the outer edges of the leaves.

In testimony whereof I affix my signature.
PAUL O. KUEHN.
